UNITED STATES PATENT OFFICE.

EUGENE M. LEDLOW, OF MCKENZIE, ALABAMA.

CLEANER FOR WIND-SHIELDS OF AUTOMOBILES.

1,097,449.

Specification of Letters Patent.

Patented May 19, 1914.

Application filed May 9, 1912. Serial No. 696,196.

To all whom it may concern:

Be it known that I, EUGENE M. LEDLOW, a citizen of the United States, residing at McKenzie, R. F. D. No. 1, in the county of 5 Covington, State of Alabama, have invented certain new and useful Improvements in Cleaners for Wind-Shields of Automobiles; and I do hereby declare the following to be a full, clear, and exact description of the invention, such as will enable others skilled in the art to which it appertains to make and use the same.

This invention relates to improvements in cleaners for automobile wind shields or the like.

One object of the invention is to provide a simple and cheap cleaning device which can be thrown into and out of operation while the machine is in movement.

Other objects and advantages will be apparent from the following description and with particular reference to the accompanying drawings.

In the drawings: Figure 1 is a front elevation of a wind shield and a portion of a dash board showing the wind shield attached thereto, Fig. 2 is a side elevation, Fig. 3 is a vertical section on the line 3—3 of Fig. 1, Fig. 4 is a vertical section on the line 4—4 of Fig. 1, Fig. 5 is an enlarged cross sectional view of the cleaning member on the line 5—5 of Fig. 1, and Fig. 6 is a vertical section on the line 6—6 of Fig. 4.

Referring particularly to the drawings, 10 represents the dash board of an automobile and 11 the frame of the wind shield. The frame 11 is secured to the dash board 10 by means of a number of the clamps 12 as shown. These clamps are placed on the dash board 20 so that the shanks rest on the upper edge thereof, the lower edge of the frame of the shield resting on the upper portions of the shanks between the heads. The screws 17 are then turned against one face of the frame 11 and dash board 10 so that the frame and dash board are securely clamped between the heads of the clamps.

In the upper portion of the frame 11 is arranged a pane of glass 19, a handle or knob 20 being secured near one edge of the glass by a screw. Secured to the frame on each side of the opening is a circular strip 21 which holds the glass pane within the opening. Formed through these strips and the frame at one side of the opening is a smaller opening 22 and through this open-

ing passes the spring-pressed bolt 23, said bolt having a thumb-piece 24 on one end for rotating the same. Rigidly secured to the bolt by the key 25, is a flanged member 25' having an arm 25 integrally formed therewith and extending out over the glass. To this arm is secured a piece of sheet metal 26, the lower edge of which is beveled as at 27, to form a knife edge and is engaged 65 against the surface of the glass. The upper portion of the metal strip is doubled longitudinally on itself as at 28, and has secured therein a piece of rubber, felt, or the like, which also bears against the face of the 70 glass. Secured on one of the strips 21 over the opening 22 is an apertured plate 30, which is provided with a raised rib 31 having formed therein four equally spaced notches 32, for the reception of lugs 33 75 formed on the head of the bolt 23.

It will be noted that the spring on the bolt 23 will normally draw the arm 25 toward the frame and the glass. In normal inoperative position the arm 25 hangs downwardly, at one side of the frame with the lugs 33 engaged in the horizontally arranged notches 32, and when it is desired to clean the glass, the thumb-piece 24 is grasped and the bolt 23 pushed inwardly 80 and rotated, to move the arm 25 to a position across the glass pane. When the thumb-piece is released, the spring will draw the arm toward the glass so that the scraper and wiper will engage thereagainst. The 85 handle 20 is then grasped and the glass pane rotated. The knife edge will scrape the glass and the wiper clean and polish the same. This can be quickly and easily done, even while the vehicle is running at 90 full speed.

What is claimed is:

1. An attachment for cleaning rotatable window panes comprising an arm for attachment to the frame of the pane and movable horizontally toward and away from the pane, and pivotally into and out of operative position, a cleaning material in the arm engaging the pane, a handle in the same for rotating the member, and means for holding 100 the arm in operative position at times, and at times in inoperative position.

2. An attachment for cleaning rotatable window panes comprising an arm for pivotal attachment to the frame of the pane 105 and movable toward and away from the pane, a scraper on the arm, a cleaning ma-

terial carried by the scraper, a spring on the pivot of the arm for holding the cleaning material in engagement with the pane, means for rotating the pane, and means carried by the pivot of the arm for engagement with means carried by the frame for holding the arm in adjusted position.

3. An attachment for cleaning rotatable window panes comprising an arm for pivotal attachment to the frame of the pane, a socketed member on the arm, a scraper formed on the socketed member, a cleaning

material in the socket of the socketed member, an apertured plate carried by the frame, and lugs on the pivot of the said arm for engagement in the apertures of the plate to hold the arm in operative position. 15

In testimony whereof, I affix my signature, in presence of two witnesses.

EUGENE M. LEDLOW.
